UNITED STATES PATENT OFFICE.

HENRY D. HINCKLEY, OF HARTFORD, CONNECTICUT, ASSIGNOR TO THE R. & H. MANUFACTURING COMPANY, OF HARTFORD, CONNECTICUT, A CORPORATION OF CONNECTICUT.

DESIGN FOR A CASING FOR VENDING-MACHINES.

45,530.

Specification for Design.

Patented Mar. 31, 1914.

Application filed November 18, 1913. Serial No. 801,750. Term of patent 3½ years.

To all whom it may concern:

Be it known that I, HENRY D. HINCKLEY, a citizen of the United States, residing at Hartford, in the county of Hartford and State of Connecticut, have invented a new, original, and ornamental Design for a Casing for Vending-Machines, of which the following is a specification, in which the accompanying drawing is a perspective view of a casing for vending-machines, showing my new design.

Referring to the drawings the casing is denoted in a general way by 2, the lower portion thereof having the forwardly extending

breast 3 over which is arranged the forwardly extending breast 4 which, however, does not extend as far forward as the breast 3. The breast 4 is surmounted by the stepped portion 5.

I claim:

The ornamental design for a casing for vending machines substantially as shown and described.

HENRY D. HINCKLEY.
